UNITED STATES PATENT OFFICE.

PAUL R. FINCH, OF DES MOINES, IOWA.

MOVEMENT-CONTROLLING DEVICE.

Application filed July 24, 1922. Serial No. 577,002.

To all whom it may concern:

Be it known that I, PAUL R. FINCH, a citizen of the United States of America, and resident of Des Moines, Polk County, Iowa, have invented a new and useful Movement-Controlling Device, of which the following is a specification.

The object of this invention is to provide improved means for controlling and retarding the movement of swinging objects, such as doors, shifting levers of motor vehicles, shifting cables of elevators, and the like.

A further object of this invention is to provide an improved mechanism for controlling the movement of objects by the resistance afforded by a liquid contained within an enclosure.

A further object of this invention is to provide means for adjusting the retarding influence of the liquid by selective control of the passages provided therefor.

A further object of this invention is to provide a movement controlling device which will permit rapid movement of an object through certain arcs and retarded movement through other arcs of travel.

With these and other objects in view, my invention consists in the construction, arrangement and combination of elements hereinafter set forth, pointed out in my claims and illustrated by the accompanying drawing, in which—

Figure 1 is a plan view showing one form of my device attached to and adapted to control the movement of a hinged door. Figure 2 is a side elevation of the device detached, a portion of the bowl being broken away to reveal interior construction. Figure 3 is a horizontal section on the line 3—3 of Figure 2.

Figure 4 is a plan view showing a different manner of mounting the device, to control the movement of a door adapted to swing in either direction from its normal closed position.

Figures 5 and 6 are plan views showing modified forms of the bowl.

Figure 7 is a plan view illustrating one form of the device mounted in such manner as to control the movement of a shifting lever of a motor vehicle.

In the construction of the device as shown the numeral 10 designates a plate, preferably formed with two margins intersecting at an angle and provided with upturned flanges

11, 12 apertured to receive screws 13 by which the device may be attached to an object. In Figure 1 the device is illustrated as attached to a door 14 connected by hinges 15 (one of which is shown) to a door casing 16, and the plate 10 may be secured to said door, or to other objects, by selective attachment of either of the flanges 11, 12, dependent upon the direction the door is adapted to swing in its frame. A bowl 17, of generally circular form, is formed on or fixed rigidly to and depends from the plate 10. A casing 18, which also may be generally circular in plan, is fixed to and rises above the plate 10, said casing and bowl communicating, if desired, through a slot such as 19, or other opening or openings in the plate 10. A shaft 20 is journaled in and centrally of the bowl 17 and casing 18, extending through a packing nut 21 in the top of the latter member. A lever 22 is fixed at one end to the projecting end of the shaft 20, and a link 23 is pivotally secured at one end to the free end of said lever. The opposite end of the link 23 is adapted for pivotal connection to an object such as the door frame, in this instance by means of a bracket 24 fixed to the top member of said frame at a point spaced from the hinge 15 and formed with a plurality of holes 25 for selective attachment of said link. A coil spring 26 is mounted around and secured at one end, in any suitable manner, to the projecting end of the shaft 20 and has its opposite end attached to the casing 18, plate 10, or some other relatively rigid portion of the device. In this instance a plate 27 is provided, attached to the casing 18, and formed with a plurality of notches 28 to receive selectively engagement of the spring 26, whereby the tension of said spring may be regulated and adjusted. It is the tendency and function of the spring 26 to apply pressure in such manner as to close the door 14 in its frame, or to move any other movable object to which the device is attached, to its normal position of rest. For a door hinged on the opposite side to that shown in Figure 1, the attachment of plate 10 would be by means of the other flange, 12, and a spring wound in the opposite direction would be employed. The action of the spring in either event is resisted and movement of the door checked and retarded by means about to be described.

Within the bowl 17 a wing or paddle 29

is fixed to the shaft 20 and extends substantially radially of the said bowl, having greater or less closeness of contact with the bottom and side wall of said bowl, and the 5 plate 10, as required for particular uses. The bowl 17 is provided with a substantially radial partition 30, which in this instance is formed, for convenience, as a sector in the side wall of the bowl. A quantity 10 of suitable liquid such as oil is placed within the bowl 17 and movement of the shaft and parts connected therewith is resisted by such liquid, which may pass in a restricted movement from one side to the other of the 15 bowl 17. Thus closing movement of the door is checked and retarded against the action of the spring 26. In the event the slot 19 (Figure 3) is 20 employed, affording communication between the bowl 17 and casing 18, it is obvious that liquid may pass more freely, and will offer less resistance to the wing or paddle 29 while traversing the arc subtended 25 by said slot, so that the movement of the door 14 may be more rapid throughout certain arcs and then restricted materially throughout other arcs, as for instance just prior to reaching closed position, thus preventing slamming of the door. It is ob- 30 vious that selective arrangement of communication between the bowl 17 and casing 18 may be employed, or may be omitted entirely for some uses. In Figure 5 I have 35 shown a form of bowl 17' which is employed without a slotted or apertured plate but is formed in its bottom with an arcuate groove 31 over which the wing or paddle 29 passes throughout a portion of its move- 40 ment, said groove permitting more rapid passage of, and hence less resistance by, the liquid throughout a certain portion or arc of movement of the wing or paddle. Cooperating with the groove 31 may be an enlargement 45 of the inner diameter of the side wall of the bowl 17', as indicated at 32, permitting passage of liquid more freely past the free end of the wing or paddle. In Figure 50 6 is shown a further modified form of bowl 17" having spaced arcuate grooves 31', 31" arranged near the limits of travel of the wing or paddle, and also cooperating enlargement of diameter of the bowl, as at 32', 32". The location, number and length of 55 the slots 19, grooves 31, 31', 31" and the parts 32, 32', 32" may be varied at will to suit the need in particular instances and the desired restriction and retardation of the paddle, throughout certain arcs. 60 It will be noted that where such openings or slots between the two chambers are employed, in a movement as of opening the door a partial vacuum is caused in the bowl 17 between the partition 30 and moving wing or paddle 29 as the space between them

is enlarged, which would not be a great resistance to such movement, and the casing 18 being partially filled with air and containing some of the liquid, the forcing of a small amount more of the liquid through the opening, such as 19, will compress the air in casing 18 only slightly, which likewise would not offer great resistance to the opening movement. It will also be seen that when the wing or paddle 29 reaches a position where the opening 19 vents into that portion of the bowl behind the wing or paddle, or that part containing the partial vacuum, the said vacuum and air pressure above referred to will cooperate to draw and force the amount of liquid displaced back into the space between the paddle and partition 30. Thus any reverse movement of the door could be resisted by the liquid as described. 70 75 80 85

Also a passage 33 (Figure 3) may be provided through the partition 30, controlled by a valve 34, to provide a controlled communication between the pressure and vacuum sides of the wing or paddle, thus 90 providing means for adjusting from time to time the amount of resistance afforded, and also the speed of movement during the resisted portion thereof.

It will be seen that this mechanism will 95 for some purposes be satisfactory without the opening 19, as it may then be made to control movements in either direction throughout different arcs to be described by the lever 22. For such purpose the de- 100 vice is illustrated in Figure 4 as applied to a door such as 14' adapted to swing in either direction through an opening. In this instance the plate 10 and members carried thereby is mounted on the door frame 105 or casing 16', while the bracket 24 is carried by the door. The device may also be employed in a similar manner for controlling an elevator shifting cable and many other mechanical devices. 110

Another of these uses is illustrated in Figure 7, in which the relatively immovable object is the foot board 34, or similar member, of a motor vehicle, and the movable member to be controlled is a foot pedal 35 connected through a rock shaft 36 to the clutch of the transmission mechanism of the vehicle. The plate 10, with members carried thereby, is mounted on the foot board 34, with the lever 22 extending toward the pedal 35 and flexibly connected thereto by a link 23'. In this instance the link 23' is provided with a turnbuckle 37 whereby the effective length of the link may be adjusted. In a manner similar to that heretofore described, the device controls and retards the movement of the clutch controlling pedal, so that a careless or inefficient driver cannot allow the clutch to engage too quickly by sudden release of pressure on the 115 120 125 130

pedal 35, the device being adapted to retard return movement of said lever or pedal just prior to engagement of the clutch.

The uses illustrated and described are illustrative of many to which my invention may be applied, the movements of the lever 22 being controlled if mounted either on a moving or a stationary object and having connection to another object for the purpose 10 of controlling the movements of either or both of the objects. Where no initiative movement is required no spring is necessary, as illustrated in Figure 4 where the swinging door is provided with means affording 15 the impulse to return it to its normal position.

I claim as my invention—

1. The combination with a fixed and a movable object, of a receptacle adapted to 20 be fixed rigidly to one of said objects, a shaft journaled in said receptacle, a lever fixed to said shaft, a link flexibly connecting said lever to the other of said objects, said receptacle being provided with a transverse 25 partition, a wing or paddle on said shaft within said receptacle and movable to approach or retreat from either side of said partition, said receptacle adapted to contain a liquid offering resistance to movement of 30 said paddle relative to said partition.

2. The combination with a fixed and a movable object, of a receptacle adapted to 35 be fixed rigidly to one of said objects, a shaft journaled in said receptacle, a lever fixed to said shaft, a link flexibly connecting said lever to the other of said objects, said receptacle being formed with a radial partition, a wing on said shaft extending radially of said receptacle and movable to approach or retreat from either side of said 40 partition, said receptacle adapted to contain a liquid offering resistance to movement of said paddle relative to said partition, said receptacle being provided with 45 openings for more rapid escape of said liquid throughout certain arcs of movement of said wing.

3. A movement controlling device, comprising a chamber, a member adapted for 50 rocking movement therein, said chamber adapted to contain a liquid directly resisting certain movements of said rocking member, and means whereby such resistance may be transmitted to one or more objects for 55 controlling certain movements thereof, said chamber adapted to be mounted on one of said objects in selected position whereby such resistance is created selectively in either direction of movement of another 60 object.

4. A movement controlling device, comprising a receptacle adapted to be attached to an object, said receptacle formed with a circular chamber adapted to contain a 65 liquid, said chamber being formed with a

single substantially radial partition, a rocking member suitably journaled in said receptacle and extending outside the same, means for flexibly connecting said rocking member to another object, movement of said 70 rocking member relative to either side of said partition being controlled by resistance afforded by the liquid within said chamber, whereby movement of one of said objects relative to the other is controlled. 75

5. A movement controlling device, comprising two receptacles mounted in contiguous relation, the first receptacle being of circular form and provided with a substantially radial partition, a rocking member 80 suitably journaled in the first receptacle and movable relative to said partition, said receptacle adapted to contain a liquid offering resistance to the movement of said rocking member, and an 85 opening from the first to the second receptacle for relatively free passage of liquid during certain arcs of movement of said rocking member, whereby movement of said rocking member is resisted throughout certain arcs to a greater degree than a reverse movement through the same arc, together with a valve-controlled passage through said partition. 90

6. A movement controlling device, comprising a chamber of circular form provided with a single substantially radial partition, a rocking member journaled in said chamber and having an imperforate radial wing 95 adapted for movement relative to said partition and dividing the chamber into two parts of variable size, a liquid being contained within said chamber and adapted for restricted passage about said wing from one part to the other of said chamber, said 100 chamber being provided with means for more free passage of said liquid about said wing throughout certain arcs of movement of said wing thus producing a differential 105 resistance to movement of said wing, and means whereby said resistance may be transmitted to one or more objects to control 110 movements thereof.

7. A movement controlling device comprising a chamber of substantially circular form and provided with a substantially radial partition, a rocking member in said chamber formed with a wing extending substantially radially of the chamber, a liquid in said chamber adapted to offer differential resistance to movement of the wing on said rocking member, said chamber also being formed throughout certain arcs with enlargements permitting more free passage of said liquid, whereby throughout certain 120 arcs said enlargements permit venting past the wing of said rocking member sufficiently to set up a greater pressure on one side of said wing than on the other, and means for transmitting such resistance to one or 125

more objects to control the movements thereof.

8. A movement controlling device, comprising a receptacle formed with two straight walls meeting at an angle, a radial partition in said receptacle, a shaft mounted for oscillation axially of said receptacle, a wing fixed to said shaft and extending radially of said receptacle, said wing being movable to approach or retreat from either side of said partition, said receptacle adapted to contain a fluid, means being provided for the variable passage of said fluid about said wing thus affording variable resistance to oscillation of said shaft, said shaft being provided with means for connection to one of two relatively movable objects, said receptacle being adapted for mounting on the other of said objects by means of either of said straight walls, thus providing means for determining the direction in which resistance will be created to movement of one of said objects relatively to the other.

9. A movement controlling device, comprising a casing formed with a main chamber and an auxiliary chamber in different planes, said casing being formed with two flanges intersecting at an angle, the main chamber being formed with a radial partition, a shaft mounted for oscillation in said casing, a wing fixed to said shaft and extending radially of the main chamber and dividing the same into a vacuum and a pressure compartment, said main chamber adapted to contain a fluid, communication being provided from said main to the auxiliary chamber for passage of said fluid, means for connecting said shaft to one of two relatively movable objects, said casing being adapted to be mounted on the other of said objects by means of one or the other of said flanges. 25 30 35 40

Signed at Des Moines, in the county of Polk and State of Iowa, this 19th day of July, 1922.

PAUL R. FINCH.
